JOURNAL BOX

Harry Fox, Soldier Summit, Utah

Application May 14, 1937, Serial No. 142,572

2 Claims. (Cl. 308—89.1)

My invention relates to railroad journal boxes and has for its object to provide a new and efficient method of, and device for, holding the packing in the journal boxing from working out, leaving the boxing dry or from wadding into the outer end being forced from the boxing.

A further object is to provide a journal box which will be provided with a curved sharp pointed claw curved outwardly and backwardly slightly with a sharp point to engage and hold the journal box packing or waste from lateral movement. In cases of extreme cold weather when the car is idle any length of time the waste freezes and when started up it is wound around the journal and forced out of the door or held near the door and around the end of the journal collar and not in any way accomplishing its purpose, causing a hot box in the journal but with these claws the waste is held in proper position for complete lubrication of the journal at all times.

These objects I accomplish with the boxing shown in the accompanying drawing in which similar numerals and letters of reference indicate like parts throughout the several views and as described in the specification forming a part of this application and pointed out in the appended claims.

In the drawing

30 Figure 1 is a vertical section of a journal box and journal parts shown sectioned, and parts cut away.

Figure 2 is a section on line 2—2 of Figure 1.

Figure 3 is a section on line 3—3 of Figure 1.

35 In the drawing I have shown the journal box as A, the cover or lid therefor as B, and the journal as C. The bearing block is shown as E and the inside of the box A is provided with two rows of inwardly extended downwardly tilted curved claws 5 and 6 with the row 5 of claws formed on

the box in alignment with the center line of the journal and with the row 6 made longer and extending in farther and on a level below the center line but, spaced above the bottom line of the journal. The journal is provided with the usual collar and fillet and the dust slide is formed in the journal box end. The claws 5 have their inner end 7 sharpened and curved back slightly toward the side wall of the journal box and the claws 6 have their ends 8 pointed and also curved back with the base 9 of the claw formed integral with the side wall of the box. The lower row 6 of claws must not be too long so as to interfere with the normal movement of the journal but, each row must be of sufficient length and sharpened to engage in and hold the packing waste in place so that no amount of cold or twisting will remove it from the claws. Thus, providing an improvement over the present methods of packing journal boxes.

Having thus described my invention I desire to secure by Letters Patent and claim:

1. In a journal box of the class described, the combination of a box; a journal therein; a row of inwardly extended claws formed integral with 25 and on the inside of each side of the journal box on the center line of said journal, said claws being curved inwardly and downwardly and back slightly toward the wall of the box; and a lower parallel row of claws made longer but of the 30 same shape.

2. In a journal box of the class described, the combination of a box; and spaced apart individual tapered and sharpened claws, formed integral with said box and in parallel rows along each 35 side wall of said box with the end of each claw hooked inwardly slightly toward the wall of the box.

HARRY FOX.
